IMPROVEMENT IN COMBS.

IGNATIUS RICE, OF NEW YORK.

Letters Patent No. 59,926, dated November 20, 1866.

SPECIFICATION

Of an Improved Comb, invented by IGNATIUS RICE, of New York, in the county of New York, and State of New York.

My invention consists of a long comb, of the usual form, having a spring-band or strip of metal secured to the back or rim by rivets or otherwise, said rivets, or other fastening, being so placed as to leave short spaces of from one to three, or more, inches between the points of fastening, in order that, when the comb is sprung open to be inserted in the hair of the wearer, the said metallic strip or band shall give to the comb additional elasticity and strength. Combs made in this way, besides being stronger and more elastic, are much more durable than those now in use.

In the accompanying drawings—

Figure 1 is a top-view of my improved comb.

Figure 2 is a vertical section through the centre of the comb, showing the parts to the left of the line *x* *x*, fig. 1.

Figure 3 is a vertical section through the centre of the comb, showing the parts to the right of the line *x* *x*, fig. 1.

A is the back or rim of the comb to which the metallic strip or band *B* is fastened by the rivets *a*, *b*, *c*, *d*, and *e*. These rivets hold the comb and band immovably together wherever they are inserted, while that part of the band between the rivets is free to bend out from the comb when the comb is sprung open, thus adding its elasticity to that of the comb, and thereby aiding it to clasp the head of the wearer more firmly, and rendering the comb much stronger. It also adds greatly to the durability of the comb, as it is not so likely to become broken by bending, or by any light blow or shock which it is liable to receive. I sometimes put a false rivet in, in place of the rivet *c*, as seen at *f*, in fig. 1. By using this false rivet I avoid making a hole through the back or rim of the comb at the point equally distant from the ends, and it is therefore capable of being bent more easily, but it loses in elasticity and stiffness when compared with the comb shown in fig. 2. The band *B* may be made of polished steel, or other elastic metal, and the natural or artificial oil which is present in the hair of the wearer will preserve the said band from rusting or tarnishing. A great variety of ornamental forms may be given to the band and rivets, as well as to the comb itself, which will add very materially to the beauty of the article produced.

Having thus fully described my invention I claim the combination of the elastic spring-band, with the comb, in the manner and for the purpose set forth.
